UNITED STATES PATENT OFFICE.

HENRY E. RATHBUN, OF WORCESTER, MASSACHUSETTS.

PORCH-SHADE.

1,268,490.

Specification of Letters Patent.

Patented June 4, 1918.

Application filed November 15, 1917. Serial No. 202,220.

To all whom it may concern:

Be it known that I, HENRY E. RATHBUN, a citizen of the United States, residing at Worcester, in the county of Worcester and State of Massachusetts, have invented certain new and useful Improvements in Porch-Shades, of which the following is a specification.

My invention relates to porch shades or

blinds, and to that class which are made of a series of thin strips or slats, preferably of wood, secured together, and held in place by flexible strands or threads, which are interwoven or twisted about said strips or slats, in any usual and well known way, and which has a top, and bottom edge, of a plurality of strips or slats secured together, as shown in my U. S. Letters Patent, No. 1,163,951.

My invention particularly relates to an improvement in the process or method of making porch shades or blinds of the class referred to above, and the object of my invention is to reduce the cost of making porch shades or blinds of the class referred to, and also to produce porch shades or blinds with the top, and bottom edge of improved construction.

In making the porch shade or blind in the ordinary way, the body of the shade or blind is made of the desired length, and then the top, and bottom edge is made, by attaching one or more separate strips or slats to the top strip or slat of the body of the shade or blind, and to the bottom strip or slat of the body of the shade or blind, to form the top, and bottom edge. This way of making the shade or blind requires the use of extra slats or strips, which must be handled separately by the operator, and must be secured by him to the top, and to the bottom strip of the body of the shade or blind, to make the top, and bottom edge of the shade or blind.

In my improved method or process of making porch shades or blinds of the class referred to, the extra strips or slats forming the top, and bottom edge of the shade or blind, are not separate from the strips or slats forming the body of the shade or blind, but are made a part of the shade or blind the same as the other strips or slats, and they are secured to the strips or slats, forming the body of the shade or blind, by the same strands or threads which are interwoven or twisted about said strips or slats,

so that in making the top, or bottom edge of the shade or blind, no extra strips or slats, made separate from the body of the shade or blind, are required.

In weaving a shade or blind body the cords constitute the warp and the wooden strips or slats form the weft or filling, and, in accordance with the present invention, the strips or slots which are to constitute the top and bottom edges of the shade or blind form a continuous part of the woven shade fabric intermediate the ends of said fabric and preferably comprise strips or slats thicker than the strips or slats in the body of the shade or blind between the ends, or upper and lower edges, of the latter.

After the shade or blind has been made, as above described, that portion which contains the strips or slats which form the top and bottom edge of the shade or blind, is bent or folded by the operator, so that there will be a plurality of strips or slats extending one above the other, at predetermined distances, to form the top, or bottom edge of the shade or blind. The plurality of strips are secured together by nails, or otherwise, and the attaching cords or strands are then cut, in the direction of the width of the shade or blind, to separate the contiguous edges of the shade or blind.

I have shown in the drawing the different steps in my improved method or process of making shades or blinds, of the class referred to.

Referring to the drawing:

Figure 1 shows a top view of a detached section of a shade or blind, embodying my improved method of making shades or blinds.

Fig. 2 is a section on line 2, 2, Fig. 1, looking in the direction of arrow *a*, same figure.

Fig. 3 shows the first step in the formation of the top, or bottom edge of the shade.

Fig. 4 shows the second step.

Fig. 5 shows the third step, and the top, or bottom edges complete, and

Fig. 6 shows the edges shown in Fig. 5, cut apart, and separated.

In the accompanying drawing, 1 are strips or slats, preferably of wood, forming the body of a shade or blind. 2 are two strips or slats preferably of curved or rounded shape on one side, which form the outer side of the top, or bottom edge of the shade, and 3 are strips, preferably made

thicker than the strips 1, which form the inner side of the top, or bottom edge of the shade. 4 are the strands or threads, arranged in pairs, and wrapped or twisted about the slats, 1, 3, and 2, in the usual and well known way, to secure them together and hold them in place.

After the shade has been made, with the slats or strips 2, and 3 forming a part thereof, as shown in Figs. 1, and 2 of the drawing, the operator, to complete the shade, moves the two strips 3, toward each other, to raise the strips 2, above the plane of the body of the shade or blind, as shown in Fig. 3. The continued movement of the strips 3 toward each other, causes the intermediate strips 1 to move down at their upper edge and toward the strips 3, as shown in Fig. 4, and the continued movement of the strips 3 toward each other, causes the intermediate strips 1 to rest on the strips 3, and the strips 2 to rest on the strips 1, as shown in Fig. 5. The three strips 2, 1, and 3 are then secured together by the operator, preferably by brads or nails 5. After the strips have been secured together by the nails 5, the cord or strands 4, connecting the strips 2 together, as shown at 4' in Fig. 5, are cut, leaving the completed top, or bottom edge on the shade, as shown in Fig. 6. The fastening nails or brads clamp the severed warp cords between the attached strips and thus securely hold the ends thereof in place.

I have shown in the drawing, one of the strips 3 forming a part of the top, or bottom edge of the shade thicker than the strips 1 forming the body of the shade, and I prefer this construction, as the brads or nails will hold better in a thicker strip, but a strip of the same thickness as the strips in the body of the shade may be used, instead of a thicker strip. The strips 2, forming the outside of the top, or bottom edge of the shade are shown as curved or rounded on one side, and I prefer this construction, but said strips may be flat, or of a different shape on the outside, if preferred.

The advantages of my improvements in the manufacture of porch shades or blinds of the class referred to, will be readily appreciated by those skilled in the art.

In making the porch shade or blind, the strips or slats forming the top, or bottom edge of the shade or blind, form a part of the shade or blind, and are connected to the ordinary strips or slats by the same strands or threads which connect the ordinary strips or slats together, thus doing away with the

use of any extra slats or strips, which have to be handled separately, and attached to the strips forming the body of the shade.

It will be understood that the details of construction of my improvements in the method or process of making porch shades of the class referred to, may be varied if desired.

The essential feature of my improvements consists in weaving into the shade or blind, and making a part thereof, in making the body of the shade or blind, the strips or slats, which make the top, or bottom edge of the shade or blind.

Having thus described my invention, what I claim as new and desire to secure by Letters Patent is:

1. A porch shade or blind having the top edge and the bottom edge comprising a plurality of strips or slats, of a different thickness, which are woven in with the strips or slats forming the body of the shade or blind.

2. A porch shade or blind having the top edge, or the bottom edge, or both the top and bottom edges, comprising a plurality of strips or slats, one or more of which is thicker than the strips or slats in the body of the shade or blind, and which are woven in with said strips or slats forming the body of the shade or blind.

3. An improved method of making the top edge, or the bottom edge, or both the top and bottom edges of a porch shade or blind, which consists in weaving in with the relatively thin strips forming the body of the shade, thicker strips in adjacent pairs, then folding the thicker strips upon each other, with an intervening thin strip, and then separating the pairs of folded strips from each other by severing the warp cords of the fabric.

4. A porch shade or blind having a top or bottom edge, or both top and bottom edges, comprising strips or slats which are thicker than the strips or slats in the body of the shade or blind and which are connected with the said strips or slats forming the body of the shade or blind by the same warp cords which connect the body strips together, said top or top and bottom edge strips being nailed together, one of said thicker strips or slats being flat and the other having one flat face and one curved or rounded face.

HENRY E. RATHBUN.
